UNITED STATES PATENT OFFICE.

BENJAMIN D. GOLDBERG, OF BROOKLYN, NEW YORK.

PRESSING DEVICE.

Application filed May 16, 1923. Serial No. 639,257.

To all whom it may concern:

Be it known that I, BENJAMIN D. GOLDBERG, a citizen of the United States, and a resident of Brooklyn, in the county of Kings and State of New York, have invented certain new and useful Improvements in Pressing Devices, of which the following is a specification.

My invention relates to pressboards or pressing devices designed for use in pressing fabrics or clothing and so constructed as to afford a supporting surface having a large number of fine metal teeth or points upon which the fabric is sustained during the operation.

In devices of this nature it has been customary to employ what is known as card clothing comprising numerous bent pieces of hard drawn wire called dents or teeth which are fixed in a suitable foundation consisting usually of several layers of cloth or textile fabric cemented together to form a good supporting body, the whole comprising substantially a wire brush the individual teeth or dents of which are very close together over the whole surface and form a great number of points or needles that afford a support to the fabric when subjected to the action of the pressing iron.

This form of card or brush is subject to several objections among which may be mentioned that when a hot iron in conjunction with moisture is applied in the pressing operation, the steam developed by the hot iron condenses on the foundation and the wire itself becomes oxidized, thereby destroying the device. Furthermore the heat softens the cement of the cloth foundation, thus permitting the position of the wires to be disturbed, and also the heat may cause them to lose their temper and permit them to bend under the pressure, thereby destroying the efficiency of the entire device.

The object of my present invention is to avoid the objections and disadvantages incident to the ordinary construction of card clothing and to make it possible to dispense with the employment of any cloth or textile material in the device whatever.

My present invention consists in constructing the card or brush upon which the fabric is sustained in the pressing operation from a multiplicity of thin strips or plates of metal each formed on one edge with a line of closely spaced points or teeth, said

plates of any desired number being assembled and held in position side by side in a close mass, all forming in co-operation, by their points or teeth, a surface for the pressing device of any desired area consisting entirely of closely arranged metal points or teeth over the entire surface, acting in the same manner as the teeth or dents of the usual card clothing.

In carrying out my invention the said teeth or points are preferably formed in a conical shape so as to afford a widened base for the point itself, thereby strengthening the same against turning or denting under the pressure. The individual plates themselves may be each formed with a number of depressions in a side thereof for the purpose of affording passages through the mass of plates for condensed moisture or for the passage of a supply of steam or moisture upward through the body of plates. In effect my device is made of solid metal and incapable of absorbing moisture. Being of metal, however, it is adapted to become heated in the process of pressing and any moisture collected in the device will be turned into steam or vapor thus increasing the efficiency of the device and avoiding rusting. Inasmuch as the bodies of the plates or strips are in firm side contact with one another and form together a solid, metal body, and the teeth themselves have enlarged bases, it is obvious that my present device will be extremely strong and will not give or dent upon the application of the pressing iron since there is no cloth cemented foundation. Furthermore, inasmuch as my present device is made wholly of metal, it is extremely sanitary.

My invention further consists in details of construction more particularly pointed out in connection with the accompanying drawings and specified in the claims.

In the accompanying drawings:

Fig. 1 is a general view of a steam or similar pressing board for pressing fabrics provided with a pressing device constructed in accordance with my invention. In this figure the fine points are indicated at one end of the top surface or area, said points being repeated in practice, of course, over the whole supporting area on the upper surface of the pressboard here shown as an elongated board with rounded ends.

Fig. 2 is a plan of the base upon which

the assembly of metal strips is supported, said strips or plates being removed.

Fig. 3 is a cross-section on the line 3—3 of Fig. 2.

5 Fig. 4 is a side elevation of one of the strips.

Fig. 5 is a bottom edge view thereof.

Fig. 6 is a vertical cross-section through one of the strips upon the line of one of the 10 points.

Fig. 7 shows the device in plan with a portion of the assembly of strips in place.

Fig. 8 is a perspective view of the bottom side of a mass of the strips enlarged in size.

15 1 indicates an individual thin metal strip or plate formed in proper shape for producing, by assembly with a number of others, a pressing device embodying my invention.

Referring to Fig. 4, the individual points 20 or teeth of each strip are indicated at 2. These are formed in one edge of the plate or strip and may be multiplied to any desired number in each strip and are each of substantial conical form as shown in the Fig.

25 4 and in the Fig. 6 which is a vertical section through one of the points. This shape of point or tooth, by affording an enlarged base for the point, adds strength to the device. Also in a side of each strip I prefer 30 to form vertical grooves or depressions indicated at 3, the number of which may also be multiplied as desired. When the plates are assembled in close side contact with one another, these grooves or depressions 35 form in effect perforations in a metal body made up of the plates or strips and afford passageways for moisture or steam.

4 indicates a metal base upon which the strips are supported on edge and to which 40 they are locked or secured in any desired manner. Preferably I provide in each strip a notch indicated at 5 which constitutes, when the plates are assembled as shown in Fig. 8, a groove running crosswise of the strips solidly assembled together in contact 45 and operating as the groove or mortise for ways or guides 6 on the upper surface of the base 4 (Figs. 2 and 7). These ways or guides are formed as tenons co-operating 50 with the grooves 5 of the massed assembly of plates thereby locking the assemblage of plates in position against detachment from the base. Any other means might be employed, however, for holding the assembled 55 plates down upon a suitable base plate.

In the base plate are provided any suitable or desired number of openings or passageways 7 which permit the passage of steam or vapor through the base plate and 60 through the fine passages in the mass of toothed plates or strips afforded by the grooves or depressions 3 therein.

To assist in firmly holding the plates upright in position and preventing their displacement, the base plate 4 may be pro-

vided with a flange 9 bounding the assemblage of plates or strips. At one end of the assembly of strips the portion 9' of the flange may be made detachable and suitable clamping screws or other clamping means employed to press the same against the end plate or strip of the assembly, thus pressing them firmly together in solid contact with one another.

A hollow support for the device having a vapor or steam connection is indicated at 10 while the connection is indicated at 11. Evidently steam supplied through 11 and the hollow support 10 is free to pass up through the openings in the base 4 and 80 through the passageways in the solid mass of strips.

As will be seen, the base 10 for the fabric support proper mounted thereon provides a steam space underneath the whole fabric support from which steam is supplied through all portions of the fabric support for passage therethrough to the fabric being pressed.

The device may be used either under or 90 over the cloth being pressed or may be applied both under and over.

What I claim as my invention is:—

1. A pressing device consisting of thin metal plates each having an edge formed 95 into a series of fine teeth and assembled together as a mass of plates engaged with one another and held firmly in position to present a fabric supporting surface consisting of a multiplicity of compactly arranged metal points.

2. In a pressing device, a cloth support consisting of a mass of thin metal plates assembled and clamped together and each provided on its upper edge with a series of fine metal points and a multiplicity of passageways extending through the mass from the base of the points.

3. A pressing device consisting of a multiplicity of fine metal strips each provided on an edge with a series of closely spaced metal points and provided on its side with a depression, said plates being assembled and held closely together side by side in a solid mass to present a uniform surface consisting of a multiplicity of closely arranged metal points over said surface.

4. A fabric pressing device consisting of a multiplicity of thin metal plates furnished on one edge with a series of closely spaced fine metal points, a base upon which said plates are assembled side by side in contact with one another and a dovetail connection between each plate and the base.

5. A pressing device comprising a multiplicity of thin metal plates held in side contact with one another and each furnished on one edge with conical projecting points closely spaced, a metal base supporting the same, and having openings therethrough 130

and grooves upon the side of the plates forming passageways between the base of the points and the openings in the supporting base.

5 6. A pressing device comprising a multiplicity of fine metal points closely spaced to present a substantially uniform surface of points and rising from and integral with a metal body having perforations through

10 it to afford passage-ways for the flow of steam or moisture to or from the points.

7. A pressing device comprising a multiplicity of thin metal plates each furnished on its edge with closely spaced conical points and having grooves in their sides between the base of the points and the opposite edge of the plate, a metal base having a chamber communicating with said grooves, means for locking said plates down

20 upon the base and means for clamping the plates together in close side contact.

8. A pressing device comprising a multiplicity of thin metal plates having each a series of closely spaced fine metal points 25 on its edge all assembled together to present a surface of closely spaced metal points, a base having an upwardly projecting flange within which the plates are supported by their edges, means for locking the

30 plates down upon said base and means for locking the plates firmly in side contact with one another.

9. A pressing device comprising a multiplicity of thin metal plates having each a 35 series of closely spaced fine metal points on its edge all assembled together to present a surface of closely spaced metal points and means for locking the plates firmly in side contact with one another.

40 10. A pressing device comprising an assemblage of thin metal plates which are provided each on its edge with a series of closely spaced points and held in close side contact with one another, a multiplicity of 45 passages through the assembly of plates and a base plate having openings through it and supporting the assemblage of plates on their edges.

11. In a pressing device, the combination 50 of a base having openings through it, a fabric support presenting on its upper surface a multiplicity of fine supporting points rising from and integral with a substantially solid mass of metal, passages through 55 said fabric support and means for supplying steam or moisture to the openings in the

base for passage therethrough and through the passages in the fabric support.

12. In a pressing device, a fabric support presenting on its upper surface a multiplicity of fine supporting metal points integral with and projecting from a perforated metal body and means for supplying steam or moisture to the perforations. 60

13. A pressing device comprising a multiplicity of thin metal plates each having a series of closely spaced fine metal points on its edge all assembled together to present a surface of closely spaced metal points, a base having a flange within which the plates 70 are supported by their edges upon the base and means for clamping a portion of said flange against the side of the assemblage of plates. 65

14. A pressing device comprising a metal 75 base, a multiplicity of thin metal plates each provided on one edge with a series of points and upon their other edge with a notch, and tenons on the base upon which an assemblage of plates may be locked by 80 co-operation of said tenons with the grooves formed by the notches in the assembled plates and means for clamping the assemblage of plates together in side contact with one another. 85

15. In a cloth pressing device, the combination of an assemblage of thin metal plates each formed with a multiplicity of fine points on its edge and all assembled together in a solid mass and having a multiplicity of passageways through said mass, a metal base upon which said plates are supported by their edge and means for supplying steam or vapor to the passageways extending through the mass of plates. 90

16. In a pressing device, the combination with a fabric support comprising a substantially solid mass of thin metal plates presenting a multiplicity of fine points integral with the plates and having passage-ways 100 extending through the mass of a base affording a steam space beneath the fabric support for supply of steam to all parts thereof.

Signed at New York, in the county of 105 New York and State of New York, this 15th day of May, A. D. 1923.
